UNITED STATES PATENT OFFICE.

JAMES T. McMAHON, OF NEW HAVEN, CONNECTICUT, ASSIGNOR TO THE COLUMBIA AND ELECTRIC VEHICLE COMPANY, OF JERSEY CITY, NEW JERSEY, AND HARTFORD, CONNECTICUT.

DESIGN FOR A SASH-FASTENER.

SPECIFICATION forming part of Design No. 32,096, dated January 9, 1900.

Application filed November 20, 1899. Serial No. 737,701. Term of patent 14 years.

To all whom it may concern:

Be it known that I, JAMES T. McMAHON, a citizen of the United States, residing in the city of New Haven, county of New Haven, State of Connecticut, have invented and produced a certain new and original Design for Sash-Fasteners, of which the following is a specification, reference being had to the accompanying drawings, forming a part thereof.

This invention relates to sash-fasteners as used to lock window-frames in vehicles against rattling and to adjust one or more of them, as the case may demand, fixedly in position, while the configuration is such as to allow of their easy manipulation; and it consists in the design for such fasteners as shown in the accompanying drawings, in which—

Figure 1 is a plan view of my design of fastener, and Fig. 2 an elevation of the same.

My fastener, as represented in the drawings and viewed from the point of outline, has essentially two parts of its contour presenting cam or spiral surfaces at different distances from a common pivot and an intermediate portion of the outline receding from the common spiral and forming a break in the continuity of the common spiral of the two cam-surfaces.

A is the pivot cam portion. B is the outer cam portion, which portions are connected by 30 the part C, while in the pivot portion is a hole D. The contour of A from a to b bounds, in effect, a cam-surface or spiral receding in a direction a b from D. Following the contour further, about c it recedes from the 35 aforementioned spiral, forming a reentrant outline until at d it again joins what is substantially a continuation of the spiral. From d to e the contour resumes a moderate spiral or cam-like surface. From e the remaining 40 outline of the fastener is joined to a by a more or less direct line.

The characteristic feature of my design consists in the sash-fastener as illustrated, with two parts of its outline cam-like in shape. 45

I claim as my invention—

The design for a sash-fastener substantially as shown and described.

This specification signed and witnessed this 14th day of November, A. D. 1899.

JAMES T. McMAHON.
